TELEPHONE TIME-ANNOUNCING SYSTEM

Thomas W. Varley, New York, N. Y.

Application October 10, 1934, Serial No. 747,656

3 Claims. (Cl. 179—6)

This invention relates to new and useful improvements in telephone exchange systems and particularly in automatic systems in which the calling party must be notified when to begin dialing.

The object of the present invention is to provide an arrangement whereby upon the extension of a calling line to a selector switch, instead of applying the so-called dial tone to the calling line for informing the calling party that he may proceed with the dialing of the called number digits, a time-announcing device is connected with his line. Thus, in place of a mere buzz the calling party obtains some useful information, the time of the day, and by obtaining this he will know that the dialing may start. Where merely a tone is applied to the calling line, it often happens that the subscriber does not wait for the application of the tone, starts dialing too soon, with the resulting establishment of erroneous connections. It is more likely that calling subscribers will be awaiting the time announcement than the otherwise meaningless dial tone.

A further advantage of my improved system is that calling subscribers do not need to dial special numbers or call special operators in order to obtain time announcements. The tying up of expensive central office switching equipment is thus obviated.

While the invention is disclosed in combination with so-called full automatic machine switching systems, it will be obvious to those skilled in the art that it is applicable to the other types of systems also, and that the invention is not limited to any specific type of time-announcing or switching system used.

The drawing represents diagrammatically an embodiment of the present invention as applied to a machine switching system in which sequence switches are used for controlling the establishment of connections, only so much being shown of the switching system as is necessary for a clear understanding of the invention.

Referring now to the drawing, upon the removal of the receiver from the switchhook at the calling subscriber's station the magnet **M5** of the line finder **LF** is operated to extend the calling line to a trunk line **1**. One end of trunk line **1** terminates in two wipers of the line finder and the other end of the trunk line terminates in two wipers of a district selector **DS** which will be operated in accordance with the operation of the dial at the calling station to extend the connection towards the called station. Usually there will be, of course, other selectors between the district

selector and the called station and a central exchange sender may be employed for registering the impulses produced by the calling dial.

Upon the extension of the calling line to the trunk **1**, a sequence switch associated with the line finder and whose magnet is indicated at **M11** is operated, through the agency of a relay **R10** in a manner not shown in detail, to move into its second position. In this position the two left-hand contacts of sequence switch spring **G** and the upper left-hand and lower right-hand contacts of sequence switch spring **H** are closed, extending the calling line through the line finder wipers, the trunk line **1**, the sequence switch springs **G** and **H**, conductors **2**, to the secondary winding of a transformer **3** through which, in a manner to be presently described, the time announcements are conveyed to the calling party.

When the subscriber hears the time announcement, he may dial. This will make and break the circuit of an impulse relay **R9** which, through its armature and back contact, controls the circuit of operating magnet **M18** of the district selector **DS** and a slow-acting relay **R18**. Upon the energization of relay **R18** a circuit is closed from ground, through the front contact and armature of relay **R18** to energize relay **R10**. During the sending of the first group of impulses the relay **R18** being slow to release, remains energized, but upon the termination of the first digit, the line circuit is interrupted long enough to permit the deenergization of relay **R18**, whereupon the relay **R10** becomes deenergized and permits the sequence switch magnet **M11** to move the sequence switch out of position **2**, whereupon the upper left-hand contact of sequence switch spring **G** and the lower right-hand contact of sequence switch spring **H** are opened and the time-announcing circuit is severed from the calling line.

The manner in which sequence switch springs **G** and **H** and the circuits of the district selector are operated is well known to those skilled in the art. The details are disclosed in volume 3 of Automatic Telephone Systems (London 1924) by William Aitken, Fig. 112, page 272, being particularly referred to. The calling party may now proceed with the dialing of the further digits in the usual manner.

The announcing system consists of a main shaft **5** which may be driven by a suitable time-controlled motor **6** connected to said shaft by a pulley **7**. The shaft carries two glass photographic plates or discs **8** and **9**, together with a worm gear **10** and a switching cam **11**. The worm gear **10** drives two commutators **12** and **13**, which are connected by an intermediate gear, and the cam **11**

controls switching mechanism for opening and closing an electrical circuit.

The discs 8 and 9 are centrally positioned between the arms of carriages 14 and 15, respectively. These carriages are reciprocally mounted on respective pairs of parallel rods 16, 16 and 17, 17 and are held in normal position by means of weights 18 which are suitably secured to their lower portions. The discs 8 and 9 each carry half circle concentric photographic voice records. For instance, the first record on disc 8 or the "minute" record would be the word "o'clock", the second the word "one" and the third the word "two" and so on to the sixtieth record on which would be the words "fifty-nine".

The disc 9 or "hour" record carries twelve half circle concentric records, the first record being that of the word "one" and the last of the word "twelve". These voice records are made in any well known manner upon a photographic film which forms a part of the transparent discs. The carriages 14 and 15 have light projectors 19 and 20, fixedly mounted upon one of their arms at one side of the rods, and on the other arms of the carriages opposite the projectors are fixedly mounted photoelectric cells 21 and 22. The cells are equipped with appropriate lenses for concentrating or focusing the light rays from the projectors onto and through the photographic records to the sensitive areas in said light cells, and these cells are connected by suitable circuits to the amplifiers 23 and 24. The output circuits of the amplifiers are connected by means of a switching circuit to the primary of a repeating coil 25 whose secondary is 3.

If the optical system, say on carriage 14, is properly adjusted so that a beam of light passes from projector 19 through one of the photographic records on disc 8, and if disc 8 is rotated at the proper speed the word or words originally impressed photographically upon the disc will be reproduced over the announcing circuit by means of the light cell 21 and the amplifier 23. This is also true, of course, with regard to the operation of the optical system in connection with disc 9. It is evident, therefore, that with the two discs 8 and 9 in operation combined with the optical systems, a constant repetition of words impressed on the discs may be obtained at each revolution, and if carriages 14 and 15 be moved forward the width of one record a new announcement may be obtained.

In order to announce the hour ahead of the minute, the discs are staggered with respect to each other; that is, they are so placed on the shaft 5 that one is reproducing while the other is silent. In order to arrange for the proper sequence of the announcements the cam 11 is so set with relation to the two discs that the hour announcement always precedes the "o'clock" or "minutes" announcement. This is accomplished by the switch 26 under control of the cam 11. It will be noted that during one-half of the revolution of cam 11 contact is made with the output circuit of amplifier 24 and during the other half of the revolution, contact is made with the output circuit of amplifier 23. A condenser 27 is inserted in the circuit connected with the amplifier 23, and an additional condenser 28 is connected in the circuit of amplifier 24 to prevent direct current flow.

The commutator 12 revolves once a minute and projections on this commutator operate switches 29 and 30 once per minute. The projections are offset as regards each other and are indi-

vidual to the switches 29 and 30. The function of switch 29 when operated is, first, to open the output of either amplifier and second, to close momentarily a circuit through the stepping magnet 31 which moves carriage 14 forward one notch, bringing a new record into place. The return of switch 29 to normal reconnects the output of the two amplifiers under control of cam 11 to the common repeating coil 25, the secondary of which is connected to a common announcing circuit throughout the exchange.

In the operation of the system it is necessary of course to return the carriage 14 to its normal position once an hour, and the carriage 15 to its normal position once in twelve hours. This is accomplished by switch 30 in combination with switches 32 and 33 on commutator 13, which makes one revolution in twelve hours and is provided with twelve projecting points, one of the points being longer than the others. The return of the "minute" carriage 14 is accomplished as follows: During the last part of the announcement of the fifty-ninth minute one of the points on cam 13 makes contact with switch 32, and closes a circuit therethrough from battery, inner make contact of switch 30, winding of stepping magnet 35 to ground. The closure of this circuit operates relay 35 which causes the pawl mechanism associated therewith to engage the teeth of the carriage 15 and step the carriage forward one tooth in order that a new record of a new hour may be announced. A parallel circuit is closed simultaneously with that just described for operating the stepping magnet 35 associated with the carriage 15, which extends from the inner make contact of switch 30 through the winding of release magnet 34, associated with carriage 14 to ground. The closure of this circuit causes the operation of magnet 34 which disengages its pawl from the teeth provided upon said carriage, whereupon it is returned to normal by the weight 18. The switch 30 releases after making the momentary contact just described, and immediate contact is made with switches 29, and a circuit is closed through the left contact of said switch from battery, primary winding of repeating coil 25, to ground through the winding of stepping magnet 31 associated with carriage 14. The closure of this circuit operates stepping magnet 31 which causes the carriage to be moved along its rods to again start off with the new "minute" announcement.

The long point on cam 13 which makes contact with switch 33 once in twelve hours is slightly offset with respect to the shorter tooth on the opposite side of said cam so that contact will be first made by the long tooth to close switch 33 and immediately thereafter contact will be made with switch 32 by the oppositely positioned shorter tooth. The closure of switch 33 establishes a circuit through the make contact of this switch from battery, middle make contact of switch 30, winding of release magnet 36 associated with carriage 15 to ground. The closure of this circuit energizes release magnet 36 which withdraws its pawl from the teeth of said carriage and allows it to be returned by means of the weight 18 to its normal position. Immediately after carriage 15 is restored to normal, the circuit previously described for operating stepping magnet 35 is closed through switches 30 and 32, whereupon said carriage is again stepped upward to announce the hour "one", and upon the breaking of contact of switch 30, a circuit is closed through the make contact of switch 29, as above described, for oper-

ating stepping magnet 31 associated with carriage 14 to cause it to step upward to announce the minute "one". The function of the lower or back contact of switch 30 is to open the output circuit 5 of either amplifier while carriages 14 or 15 are in motion, thus preventing imperfect or partial announcements being made.

The carriages 14 and 15 are thus successively advanced with their optical systems in respective 10 synchronism with their photographic discs so that it is possible to make a constant announcement of the time throughout each minute except for a few seconds at the close of each minute and hour when it is necessary to open the announcing circuit 15 to allow the switches to set the apparatus for a new minute or for a new minute and hour as the case may be.

During the periods the amplifier 23 is connected with the optical system of carriage 14, a 20 circuit is closed from ground through the output of said amplifier, condenser 27, left make contact of switch 26, right make contact of switch 29, lower make contact of switch 30, primary winding of repeating coil 25 to battery. 25 During the alternate periods of connection of the amplifier 24 with the optical system of carriage 15, a circuit is closed from ground, through the output of amplifier 26, condenser 28, right make contact of switch 24, and thence along the same path as that just outlined in connection 30 with the output circuit of amplifier 23. In this manner time announcements will be made according to well known principles through the 35 repeating coil 3.

It will be obvious to those skilled in the art that various modifications of the invention may be

practiced without departing from the spirit thereof as defined in the claims.

What is claimed is:

1. In an automatic telephone exchange system, telephone lines, means including a selector switch for establishing a connection between a calling and a called line under the control of a calling party, automatic means for connecting a calling line with said selector switch, a time-announcing unit, and means for associating said unit with the calling line upon the operation of said automatic means and until said selector is operated under the control of the calling party. 5

2. In an automatic telephone exchange system, telephone lines, means including a selector switch for establishing a connection between a calling and a called line under the control of a calling party, automatic means for connecting a calling line with said selector switch, a time-announcing unit, means for automatically connecting said unit with the calling line upon the operation of said automatic means, and means operative upon the actuation of said selector switch for disconnecting said unit from the calling line. 10

3. In an automatic telephone exchange system, telephone lines, means including a selector switch for establishing a connection between a calling and a called line under the control of a calling party, automatic means including a line finder 15 for connecting a calling line with said selector switch, a time-announcing unit, means operable upon the seizure of the calling line by the line finder for connecting said unit with the latter, and means operable upon the actuation of said selector for disconnecting said unit. 20

THOMAS W. VARLEY.
